UNITED STATES PATENT OFFICE

101,159

DESIGN FOR A RUG

Lucien Biva, New York, N. Y., assignor to Otto Timme, doing business as E. F. Timme & Son, New York, N. Y.

Application July 28, 1936, Serial No. 64,095

Term of patent 7 years

To all whom it may concern:

Be it known that I, Lucien Biva, a citizen of the United States, and a resident of the Borough of Bronx, county of Bronx, city and State of New York, have invented the new, original, and ornamental Design for a Rug, of which the following is a specification, reference being had to the accompanying drawing, forming part thereof.

The figure is a plan view of a portion of the rug, showing my new design.

The drawing shows the design embodied in a rug, approximately three-fourths of the rug being shown. In the complete rug the lower end will embody the design as shown at the upper end, the elements being reversed where required.

I claim:

The ornamental design for a rug, as shown and described.

LUCIEN BIVA.
